ATTORNEYS.

UNITED STATES PATENT OFFICE.

GEORGE W. THOMPSON, OF SAG HARBOR, NEW YORK.

METALLIC RAILROAD-TIE.

SPECIFICATION forming part of Letters Patent No. 394,738, dated December 18, 1888.

Application filed February 21, 1888. Serial No. 264,767. (No model.)

To all whom it may concern:

Be it known that I, GEORGE W. THOMPSON, of Sag Harbor, in the county of Suffolk and State of New York, have invented a new and 5 Improved Attachment for Metallic Railroad-Ties, of which the following is a full, clear, and exact description.

My invention is an improvement in the class of metallic tubular ties having bearing-blocks 10 arranged within them for supporting their top portions when a train is passing over the rails laid thereon. Heretofore such bearing-blocks have been made longer than the distance between the heads of the bolts that secure the 15 rails to the tie, and have also been provided with openings to receive the heads of such bolts. The ties to which such blocks were applied were necessarily made open on the under side to enable the rail-bolts to be inserted 20 through the openings in the blocks.

In my invention the bottom of the tie is closed, or nearly so, and the bearing-blocks are put in place by inserting them in the ends of the ties after the inner bolts have been applied. The heads of both the inner and outer 25 bolts abut the sides of said blocks, and thus hold them in position.

The invention consists in certain novel features of construction of the railway-tie and 30 rail connections and supports, all as herein-after described and claimed.

Reference is to be had to the accompanying drawings, forming a part of this specification, in which similar letters of reference indicate 35 corresponding parts in all the figures.

Figure 1 is a plan view of a section of a railway-track laid upon my improved ties, which are broken away at their central parts. Fig. 40 Fig. 2 is a side view thereof. Fig. 3 is a transverse section taken on the line $x-x$, Fig. 1. Fig. 4 is a horizontal section taken on the line $y-y$, Fig. 2, and shows the parts as they would be 45 seen in the direction of the arrows; and Figs. 5 and 6 are detail views, which will be hereinafter particularly referred to.

The main body of my improved railroad-tie consists of a tube, A, which is preferably of rectangular cross-sectional form, produced by bending four times at right angles a rolled 50 metal plate about two feet wide, seven feet long or longer, and about three-eighths of an inch thick, more or less, the opposite edges of said

plate meeting or nearly meeting at the lower side and longitudinal center of the tube, which is about seven inches wide, five inches high, 55 and seven feet long.

The railway-rails B B of a track are held to the solid or unbroken tops of the ties by rolled or wrought metal chair-plates C, which are placed in pairs opposite each other on each 60 tie and at the opposite sides of the rails, and are fixed by bolts D to the ties, and so that horizontal or nearly horizontal flanges or lips e e, formed at the inner edges of each pair of chair-plates C C, overlap the opposite base-flanges, b b, of the rails and securely bind them to each tie, as clearly shown in the drawings.

The bolts D are passed upward through the top of the tie and the chair-plates thereon, and the heads d of the bolts rest against the under side of the tie top plate. The parts d' of the bolts which pass through the tie and chair-plates are made square or flat-sided to prevent 70 turning of them, and the upper parts of the bolts which project above the chair-plates are 75 made round and are threaded to receive nuts d', which are tightened upon the chair-plates to bind the ties, the rails, and the chair-plates together in one substantial structure along the road-bed, which may be of earth, sand, 80 gravel, or coal-dust, or may be a bridge, trestle, or other support, and the ties may be ballasted or not, as may be desirable or necessary.

I utilize the heads d of the bolts D of each pair of chair-plates C C on every tie as lateral 85 supports or braces to hold bearers E within the tubular ties and directly below the railway-rails. These bearers are applied as follows: After the inner chair-plate C of each pair of plates is fastened to the tie by its pair 90 of bolts D, the bearer E will be slipped into the end of the tie and up snugly to the heads of this pair of bolts, and when the rail B and outer chair-plate C are put in place the pair of bolts D to hold this outer plate will be applied, and so that their heads fit snugly against 95 the outer face of the bearer, which will thus be held secure against displacement to give effective support to the tubular tie where the rail crosses it, and thus largely increase the 100 durability of the ties and rails and the entire road-bed. These bearers E, which are preferably made of cast metal, are fitted fairly at the edges to the inner faces or walls of the tubu-

lar tie, and may be of any desired width, and yet be held by the heads of the chair-plate bolts, which will be made to fit the bearers. For instance, should rather broad bearers be used, the bolts D will be of ordinary form with bodies or stems concentric with their heads, as shown at the left-hand side of Figs. 3 and 4 of the drawings, and should the bearers be made narrower, the bolt-heads d will be elongated at the inside, so as to bear fairly at opposite sides of the bearer, as shown at the right-hand side of Figs. 3 and 4 and from the detail views, Figs. 5 and 6. The bolt D, having an elongated head, d, is shown in Fig. 5, while Fig. 6 shows in larger scale than the other views such a bolt as applied to the tie, chair-plate, and bearer. These elongated bolt-heads d, forming lateral supports to the bearer-blocks, may either be made in one piece with the bodies or stems of the bolts or they may be made separate, and as nut-plates, to screw onto the lower ends of the bolts, as will readily be understood.

Railroad-ties made and supporting the rails

as above described may be set about three feet apart from center to center, or much farther apart than ordinary wood ties, and will be far more durable even when not coated with coal-tar or other rust-preventing composition, which may be done to increase the durability of the ties and road-bed.

Having thus described my invention, what I claim as new, and desire to secure by Letters Patent, is—

The combination, with the rails B, clips C, and the tubular metallic tie A, having a flat bottom, of the narrow bearing-blocks E, which are set crosswise within the tie beneath said rails, and the bolts D, inserted through the ties and having rectangular heads d, which bear against the sides of said blocks and thereby support them in place, as shown and described.

GEORGE W. THOMPSON.
